200,223

MOUNT FOR AIR CONDITIONERS Charles Leslie McCrea and David B. Cross, both of
514-516 2nd St. NW, Washington, D.C.

Filed Jan. 15, 1964, Ser. No. 78,207

Term of patent 7 years

(Cl. D62—4)

FIGURE 1 is a front elevation of a mount for air conditioners embodying our new design;

FIGURE 2 is a side elevation of the mount shown in FIGURE 1;

FIGURE 3 is a top elevation of the mount shown in FIGURE 1;

FIGURE 4 is a transverse sectional view taken on the line 4—4 of FIGURE 1; and,

FIGURE 5 is a perspective view of the mount shown in FIGURE 1.

We claim:

The ornamental design for a mount for air conditioners, as shown.
